UNITED STATES PATENT OFFICE.

OTTO A. LEHMAN, OF BROOKLYN, NEW YORK.

FRAME FOR HAND-BAGS OR POCKET-BOOKS.

SPECIFICATION forming part of Letters Patent No. 364,357, dated June 7, 1887.

Application filed May 19, 1886. Serial No. 202,606. (No model.)

To all whom it may concern:

Be it known that I, OTTO A. LEHMAN, of the city of Brooklyn, in the county of Kings and State of New York, have invented a new 5 and useful Improvement in Frames for Hand-Bags or Pocket-Books, of which the following is a specification.

Although my invention is applicable to the frames of hand-bags and pocket-books of different constructions and provided with clasps or catches of different character, its advantages are particularly apparent when employed in connection with a clasp or catch such as forms the subject of my United States Patent 15 No. 338,351, dated March 23, 1886, and when used upon bags in which the bag fabric is connected with the frame by gussets, so as to form a bag with bellows-like sides.

The invention consists in a bag or pocket-book frame having horizontal tubular members, which comprise portions offset above the portions extending in opposite directions therefrom to the ends of the frame. This offsetting of portions of the frame serves to 20 strengthen the latter, and it also serves as a very convenient point for the attachment of the clasp or catch; and when a clasp or catch of the kind shown in my aforesaid patent is employed in connection with a gusset-bag the 25 catch is raised by the offset portions of the frame so that it swings above the side portions of the bag and is not liable to strike or engage said side portions.

The invention will be hereinafter more fully 30 described, and pointed out in the claims.

In the accompanying drawings, Figure 1 represents a bag having its side portions connected with the frame by gussets, and embodying my invention; and Fig. 2 is a sectional view of the upper portion of the bag and the frame.

Similar letters of reference designate corresponding parts in both figures.

A A designate the two members of the frame, 45 which are here represented as tubular, and with which the side portions, B, of the bag are connected by gussets C. The members A of the frame have between their ends and at corresponding points portions A', which are offset 50 more or less above the general top of the frame, as very clearly shown in Fig. 1. These offset

portions A' may be of any suitable length, and may vary in configuration, the only essential being that they shall be offset above the portions of the frame which extend from them in 55 opposite directions to the ends of the frame, or, in other words, that they shall be offset above the general top of the frame. This offsetting of the frame is advantageous, because it strengthens it, and it forms a very convenient place upon which to arrange the clasp or catch for securing the two members A. A of the frame together in order to close the bag.

The clasp or catch D which I have represented is like that which forms the subject of 60 my aforesaid Patent No. 338,351; and it consists of a hook which is pivoted at d to the offset portion A' of one member of the frame, and which when pressed down engages with and passes over the offset portion A' of the 65 other member of the frame. This hook is so constructed that when it is pressed down into position to close the bag its point will pass beyond the portion of the frame which has greatest projection in a direct line from the pivot 70 d, and therefore the hook will remain in secure engagement with the member or portion of the frame over which it is pressed. This construction of the frame with upward offsets, and with a hooked clasp of the kind described, 75 is particularly advantageous with a gusset-bag, because then the hook is raised by the offset portion so that it will not strike or embrace the upper edges of the bag fabric B, even though they be bent inward, as shown by 80 dotted lines in Fig. 2, and even though such side portions of the bag extend upward to a level with or slightly beyond the general top of the frame.

What I claim as my invention, and desire to 85 secure by Letters Patent, is—

1. The bag or pocket-book frame herein described, having horizontal tubular members A A, which comprise portions A', offset above the portions which extend in opposite directions to the ends of the frame, substantially as herein described.

2. The frame herein described, having at about the middle of its length portions which are offset above the general top of the frame, 90 and a catch applied to such upwardly-offset portions, substantially as herein described.

3. The combination, with the frame comprising upwardly-offset portions A', of the hooked clasp D, pivoted to one offset portion and engaging directly with the other offset portion, substantially as herein described.

4. The combination, with a bag-frame to which the upper portions of the bag fabric are connected by gussets, and which comprises portions A', offset above the general top of the

frame, of the hooked clasp D, applied to the offset portions, whereby the said clasp is prevented catching on the bag fabric when closing the bag, substantially as herein described.

OTTO A. LEHMAN.
